UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

JOURNAL BOX.

Application filed October 30, 1924. Serial No. 746,798.

The invention relates to journal boxes and more particularly to a lid construction for closing the opening in the outer end of the journal box.

5 The principal object of the invention, generally considered, is the provision of an articulated lid construction which may be readily attached and detached by utilizing a simple lever.

10 Another object of the invention is to provide a lid construction comprising a simple lid closure which is provided at its upper end with means for loosely engaging the hinge pintle, said closure member being adapted 15 to completely close the journal box opening, a spring member pivotally supported by the hinge pintle, and a lever operatively engaging said spring and arranged without said closure member and interposed between said closure 20 member and said journal box.

A still further object of the invention is to provide a simple lid construction which is so devised and arranged as to permit of an easy and rapid assembly or disassembly from 25 the journal box, said lid construction including a torsion spring member pivotally carried by the hinge pintle of said lid.

To these and other ends the invention consists of the various elements and combinations 30 of elements as hereinafter set forth.

In the drawings:

Figure 1 is a view in front elevation of a fragmentary portion of the lid and associated journal box, a portion of the lever mechanism being shown in cross-section.

35 Figure 2 is a transverse vertical sectional view of the construction shown in Figure 1.

Figure 3 is a side elevational view of a fragmentary portion of the lever.

40 Throughout the specification and drawings like parts are designated by like reference characters.

The journal box 1 is provided with side walls 2, a bottom wall 3, and a top wall or 45 roof 4 from which projects the hinge lug 5 of the usual A. R. A. construction, the said hinge lug being perforated, as at 6, for the reception of a hinge pintle or bolt 7, and being further provided with angularly disposed bearing 50 faces 8 and 9 which are adapted to cooperate with the portions of the lid construction to maintain the lid in closed and open position.

55 The closure member or lid proper comprises a plate 10 which is provided at its upper end with loops or ears 11—11 through

which the hinge bolt or pintle 7 is adapted to extend. The ears 11 are of greater diameter than the bolt 7 to provide for a limited amount of play or clearance so that the lid 10 may accommodate itself to irregularities in 60 the walls 12 of the journal box opening. Preferably, the lateral side edges of the lid are provided with inturned flanges 13 to assist in preventing the entry of dirt to the interior of the journal box. At an intermediate 65 point, preferably adjacent the center of the journal box opening, the lid 10 is provided with an outwardly projecting T-headed member 14, said member being conveniently provided with a collar 15 to engage the outer 70 face of the lid 10 and with a rivet head 16 by means of which the collar 15 is drawn into intimate contact with the adjacent exterior surface of the lid and the opening 17 through which the member 14 projects is closed against 75 the entry of dirt.

Pivottally mounted on the pintle or bolt 7 is a torsion spring 18, said spring comprising a pair of bolt engaging arms 19 and a pair of coils 20, the outer ends of which are respectively connected to the arms 19 and the inner or adjacent ends of which are connected by a rod or bar 21, all of which is clearly shown in Figure 1. The bar 21 is arranged to normally lie above and at a distance from 85 the circumference of the coil portions 20.

The numeral 22 designates generally a lever which is substantially T-shaped. The stem of the T, 23, is provided with a bifurcated end portion 24 and with marginal flanges 90 25—25, the marginal flanges being preferably extended around the lower end of the lever to points adjacent the bifurcation or slot 24, the said slot being adapted to embrace the shank of the T member 14, the head of which 95 overlies the adjacent side edges of the lever 22 between the flanges 25—25. At its upper end the lever 22 is provided with a pair of spring housings 26 each of which is adapted to partially enclose the adjacent coil portion 100 20 of the spring 18. Each spring housing is provided with exterior walls 27—27 and interior or adjacent walls 28, the walls 28 conveniently being formed as extensions of the flanges 25. Each wall 28 is provided with an 105 angularly disposed marginal slot 29, the purpose and object of which will hereinafter be described, and in the wall 30 of each slot there is provided a curved seat portion 31 for the 110 reception of the bar 21 of the spring 18. The

exterior walls 32 of the housings 26 are provided with laterally projecting flanges 33 and the upper end of the intermediate portion of the lever 22 is likewise provided with a laterally projecting flange 34, the flanges 33 and 34 being integrally connected and being adapted to form a hood partially embracing the hinge lug 5 of the said journal box. If desired, the walls 26 may conveniently be formed with laterally extending curved lugs or shoulders 35 which overlie the ears 11—11 of the cover or lid 10.

The central portion or stem of the lever 22 is provided at a point intermediate its ends with an outwardly projecting lug 36 and is further provided intermediate the lug 36 and the upper end of the lever with a second lug or outwardly projecting boss 37. Adjacent the member 14 the said intermediate portion of the lever may be provided with a bearing member 38 to engage the lid, the bearing 38 being disposed at or adjacent the intersection of the vertical and horizontal axes of the opening of the said journal box.

Owing to the necessity of utilizing spring pressure for maintaining the lid in intimate contact with the walls 12 of the journal box opening when the lid is closed and also to provide means for maintaining the lid in raised or open position so that free access may be had to the interior of the journal box, heavy spring mechanism is necessarily employed. Such heavy spring mechanism, while essential to the satisfactory operation of the lid, is disadvantageous in that, in order to assemble the lid and journal box, it is generally necessary to utilize a press to overcome the reaction of the spring and to enable the ears of the lid to be arranged in alignment with the opening in the hinge lug. Various attempts have been made to avoid the necessity of using a press or jack since it is often necessary to apply a lid to a journal box when the same is in service, and one of the objects of this invention, as has already been stated, is to provide, in combination with the various elements set forth, means whereby the lid may be readily and easily applied to a journal box without the use of a press, jack or the like. As shown in Figure 2, the arm 21 of the spring 18 is normally disposed so as to lie within the upper extremity of the slot 29 in which position the spring 18 is not under tension, and since the spring is free it will be obvious that the lid and loop portions of the spring may be readily arranged in alignment with the opening 6 of the hinge lug and the pintle 7 inserted. It is only necessary to then insert a lever or pinch bar 39, shown in dot and dash lines in Figure 2, between the arm 21 and the face of the lever 22, the lug 36 forming a convenient fulcrum point for said lever, and to then rotate the lever 39 in a counter-clockwise direction until the arm 21 of the spring 18 is moved over and

into contact with the bearing faces 31 of the walls 28, at which time the spring 18 will be energized, thus causing the lever 22 to react to maintain the lid and associated mechanism in intimate contact with the walls of the journal box opening should the lid be closed, or by the engagement of the bearing portion 40 of the lever with the bearing face 9 of the lug 5, maintain the lid in raised or open position. Should it be desired, for any reason, to remove the lid, it is only necessary to insert the lever 39 under the arm 21 with the end of the lever engaging the upper face of the lug 37 and to pry upwardly on the lever forcing the arm 21 from the bearings 31 into the position shown in dot and dash lines in Figure 2, at which time the tension on the spring being relieved, the parts may be removed with ease.

It will be observed that the lever 22 is interlockingly and slidably connected to the lid by means of the member 14. It will also be observed that when the parts are assembled not only is the lower end of the lever 22 connected to the lid 10, but the upper end of the lever is maintained in substantially normal position by reason of the position of the bar 21 of the spring in the upper ends of the slots 29. There is therefore no danger of the displacing of the lever 22 from its normal operative position upon the movement of the arm 21 to or from the seats 31.

Having now described my invention, what I claim is:

1. The combination with a journal box having a hinge lug thereon, a plate member pivotally connected to said lug, a spring member carried by said lug and pivotally movable with respect thereto, a lever mechanism engaging said plate and lug at opposite ends thereof, said lever having slots therein to accommodate a portion of said spring when the same is released from tension, said lever also having means engaging said spring when the same is energized, said spring being adapted for movement independently of said lever from either of said positions to the other.

2. In combination with a journal box having a hinge lug thereon with angularly disposed bearing faces, a lid therefor, a pintle member pivotally connecting said lid to said box by means of said hinge lug, a lever device pivotally mounted on said lid and engaging one of the bearing faces of the lug, at the opposite end thereof, for holding said lid in open or closed position, a spring member having ends thereof engaging the pintle for connecting it to the box, an intermediate portion of said spring being adjustably received in a slotted portion of said lever, said slotted portion being formed with a plurality of notches therein, whereby the intermediate portion of said spring may be moved from relatively free to stressed positions by forcing said spring from one notch to another.

3. In combination with a journal box having a hinge lug thereon with angularly disposed bearing faces, a lid therefor, a pintle member pivotally connecting said lid to said box by means of said hinge lug, a lever device movably connected at one end with respect to said lid, engaging one or the other faces of the hinge lug at its opposite end and spring means connected to said lever and hinge lug for

forcing said lever against said hinge lug, 10 whereby the lid is held in open or closed position depending on the face of the lug with which it engages the said spring means adapted to be moved from free to stressed position where it engages different portions of said 15 lever.

In testimony whereof I affix my signature.
DONALD S. BARROWS.
